UNITED STATES PATENT OFFICE.

SAMUEL G. WILKES, OF TAUNTON, MASSACHUSETTS, ASSIGNOR TO REED
AND BARTON CORPORATION, OF TAUNTON, MASSACHUSETTS.

DESIGN FOR A HANDLE FOR CUPS OR OTHER RECEPTACLES OR VESSELS.

SPECIFICATION forming part of Design No. 36,605, dated October 27, 1903.

Application filed September 25, 1903. Serial No. 174,663. Term of patent 14 years.

To all whom it may concern:

Be it known that I, SAMUEL G. WILKES, a subject of the King of Great Britain, residing at Taunton, in Bristol county and State of Massachusetts, have invented a new, original, and ornamental Design for the Handles for Cups or other Receptacles or Vessels; and I do hereby declare the accompanying drawings to be a full, clear, and exact illustration of this specification, and represent, in—

Figure 1, a side elevation or plan view of a handle embodying my design; Fig. 2, a perspective view of the same.

I claim—

The ornamental design for a handle for 15 cups, and other receptacles or vessels, as shown.

In testimony whereof I have signed my name to this specification, in the presence of two witnesses, on this 10th day of September, 20 A. D. 1903.

SAMUEL G. WILKES.
